UNITED STATES PATENT OFFICE.

CHARLES H. VINCENT, OF LYNN, MASSACHUSETTS, ASSIGNOR TO FREDERICK W. A. BERGENGREN, OF SAME PLACE, AND JOHN V. SPALDING, OF BOSTON, MASSACHUSETTS.

INDIVIDUAL CALL DEVICE FOR TELEPHONES.

SPECIFICATION forming part of Letters Patent No. 431,088, dated July 1, 1890.

Application filed August 2, 1889. Serial No. 319,549. (No model.)

To all whom it may concern:

Be it known that I, CHARLES H. VINCENT, a citizen of the United States, and a resident of Lynn, in the county of Essex and State of Massachusetts, have invented new and useful Improvements in Individual Call Devices for Telephones, of which the following, taken in connection with the accompanying drawings, is a specification.

This invention relates to improvements in call devices for telephones, and it has for its object to enable the operator at the central station to ring up any one of the telephones on the line (in a block of from two to about ten) without ringing up the others, and this I do by means of a magneto-generator of variable strength at the central office or exchange and individual call-bells on the telephones in the block system, which bells are actuated and sounded according to the strength of the magneto-electric current sent through their respective electro-magnets, as will hereinafter be more fully shown and described, reference being had to the accompanying drawings, where—

Figure 1 represents a side view of the magneto-generator, partly shown in section, the commutator, and the key-board. Fig. 2 represents a vertical cross-section of the magneto-generator. Fig. 3 represents a side elevation of one of the individual call-bells in the block system. Fig. 4 represents a longitudinal section of the commutator. Fig. 5 represents a diagram showing the magneto-generator and individual call-bells in the block system connected together for operation; and Fig. 6 represents a diagram showing the commutator and the coils of the armature on the magneto-generator.

Similar letters refer to similar parts wherever they occur on the different parts of the drawings.

a in Figs. 1, 2, and 5 represent the permanent horseshoe-magnets of the magneto-generator at the central office or exchange, and *a' a'* represent the field-magnets, as usual.

B represents the rotary armature, having its shaft journaled in suitable bearings, and preferably provided in one end with a pinion

B', meshing in the teeth of the wheel *B''*, having a crank *B³*, as is usual in magneto-generators. By turning the crank *B³* the armature *B* is set in a quick rotary motion, as usual; or said armature may be rotated by power applied to its shaft in any other suitable or equivalent manner without departing from the essence of my invention.

In the drawings I have represented the magneto-generator as connected to five individual call-bells on as many telephones on the line; but more or less telephones may be thus connected. In practice I prefer to connect ten telephones to the improved magneto-generator.

B⁴ in Fig. 4 represents the shaft of the armature, to one end of which is attached a sleeve *B⁵*, of hard rubber or other suitable insulating material. Said insulated sleeve *B⁵* is surrounded by a number of metal rings or commutator-bands *b', b'', b³, b⁴, and b⁵*, which are connected to the respective coils of wires *C', C'', C³, C⁴, and C⁵* on the armature *B* by means of the wires *c', c'', c³, c⁴, and c⁵*, as shown in Fig. 6.

The coil *C'* is connected to the coil *C''* and wire *c''* by means of the wire *d'*. The coil *C''* is connected to the coil *C³* and wire *c³* by means of the wire *d''*. The coil *C³* is connected to the coil *C⁴* and wire *c⁴* by means of the wire *d³*. The coil *C⁴* is connected to the coil *C⁵* and wire *c⁵* by means of the wire *d⁴*, and the coil *C⁵* is connected by means of the wire *d⁵* to the ground *G*, as shown in Fig. 6.

e', e'', e³, e⁴, and e⁵ represent metallic brushes, the free ends of which are held in metallic contact with the respective commutator-rings *b', b'', b³, b⁴, and b⁵*, and having their rigid ends secured in a suitable manner to the insulated bar or plate *e*, as shown in Fig. 1. The brushes *e', e'', e³, e⁴, and e⁵* are connected, respectively, to the keys *E', E'', E³, E⁴, and E⁵* by means of wires, as shown in Figs. 1 and 5.

E represents the key-board, with which either of the keys *E', E'', E³, E⁴, or E⁵* may be connected by depressing their ends, as is common in telephonic exchanges.

From the key-board *E* leads a wire *F* to

- the individual call-bells I, K, L, M, and N on the telephones in the block system, as shown in Fig. 5. The individual call I consists of the electro-magnet i and its metal frame i' .
 5 To the free end of the said frame i' is pivoted the arm i'' , and on an intermediate piece supported on said arm is hinged the armature i^3 , as shown in Fig. 3. The arm i'' is provided with a screw-threaded lever i^4 , on which is
 10 adjustably secured the weight i^5 , as shown in Figs. 3 and 5.

- i^6 is a spring interposed between the electro-magnet i and arm i'' for the purpose of holding the armature i^3 away from the electro-magnet when no current passes through the electro-magnet i , and i^7 is a regulating set-screw on the arm i'' for limiting the outward movement of the armature-arm i'' , as shown in Fig. 3.
 15 20 i^8 is an electrode secured in a suitable manner to the individual telephone on which the bell-call is used, and i^9 is the wire leading from the electro-magnet i to the electrode i^8 .
 i^{10} is the wire leading from the electro-magnet i to the next individual magnet in the block system.

- The wire F is connected to the coil of the electro-magnet i , and its frame i' connected to said wire F by means of the wire i^{12} , as shown in Figs. 3 and 5.

- I' represents the clapper-lever secured to the armature i^3 , and I'' represents the bell or bells, as is common in telephone-calls.
 $k' k'' K' K'' l' l'' L' L'' m' m'' M' M'' n'$
 35 40 $n'' N' N''$ represent corresponding parts on the respective individual bell-calls K, L, M, and N, as shown in Fig. 5.
 n^{10} represents the wire leading from the electro-magnet n to the ground G, as shown in Fig. 5.

- By adjusting the weights i^5 , k^5 , l^5 , m^5 , and n^5 on the respective call-stations I, K, L, M, and N the armature-resistance on such call-stations will be made according to the magneto-generating power of the respective coils C', C'', C³, C⁴, and C⁵, and consequently that one only of the bells in the line will be sounded that corresponds to the key on the key-board that is depressed by the operator
 45 50 at the central office or exchange, which cor-

responds to the coil on the revolving armature of the magneto-generator. Others in the circuit will not be operated owing to absence of power sufficient to attract the armatures or to excess of power by which the arms $i'' k''$ are brought in contact with the electrodes $i^8 k^8$, causing the current to be cut off from the corresponding electro-magnets, and so on.

It will be understood that a current of electricity of different intensity is employed to operate each call, and that the weights on the levers are adjusted to agree with the intensity of current necessary to operate each call; or, in other words, a current of certain intensity 65 is necessary to operate call I, a current of different intensity operates call K, and so on throughout the other calls, and thus but one call can be operated at once, and each call is operated by a current of intensity to which the 70 call is adjusted. Each call has a key to effect such operation, and each call is adjusted to suit the intensity of the current necessary to operate it.

What I wish to secure by Letters Patent, 75 and claim, is—

1. In an individual call system, the combination of the electro-magnet, the armature, hammer, and bell, the arm to which the armature is connected, the electrode or contact 80 which co-operates with the said arm, and the weighted lever connected to said arm, substantially as described.

2. In an individual call system, the combination of the magneto-generator, the commutator, the keys, the electro-magnets, the armatures, the arms to which said armatures are connected, the levers connected to said arms, the weights adjustable on said levers, and the electrodes adjacent to said arms, sub- 90 stantially as described.

In testimony whereof I have signed my name to this specification, in the presence of two subscribing witnesses, on this 24th day of July, A. D. 1889.

CHARLES H. VINCENT.
